W. F. DURFEE, OF BRIDGEPORT, CONNECTICUT.

Letters Patent No. 87,152, dated February 23, 1869.

IMPROVED CASING FOR REVERBERATORY AND OTHER FURNACES.

The Schedule referred to in these Letters Patent and making part of the same.

To all whom it may concern:

Be it known that I, W. F. DURFEE, of Bridgeport, in the county of Fairfield, and State of Connecticut, have invented a new and improved Method of Constructing the Iron Casings of Reverberatory and other Furnaces; and I do hereby declare that the following is a full and exact description thereof, which will enable others skilled in the art to make and use the same, reference being had to the accompanying drawings, forming part of this specification.

The nature of this invention consists in forming the plates which are used to encase reverberatory and other furnaces, in such manner as to avoid all risk of breakage from expansion by the heat, to which they are liable, and at the same time to diminish their size and weight, and also to so construct them that they will not radiate so much heat to the surrounding air, to the end that the construction of the furnace-casings may be cheapened, and the furnace itself worked with greater comfort to the workmen, and a diminished consumption of fuel; also to enable the furnace to be constructed and repaired with greater facility.

In the accompanying sheet of drawings—

Figure 1 represents a front elevation of a reverberating furnace cased with plates constructed according to my invention.

Figure 2 represents a horizontal section of fig. 1, on the line A B.

Figure 3 represents an elevation of one of the plates constructed according to my invention.

Figure 4 represents a horizontal section of fig. 3, on the line U V.

Similar letters of reference represent like parts.

Instead of constructing the casings of furnaces in the ordinary manner, (viz, with plain plates of iron extending from top to bottom of the furnace, which plates are from one to one and a quarter inch in thickness, and without perforations, the plates on the front of the furnace being tied to those on the back by bolts, passing through holes in the tops of the front and back plates, respectively,) I construct them in the following manner, and to make the construction clear as possible, I will describe the construction of one bay or panel of the furnace-casing, all the other bays or panels being constructed in a similar manner, for which purpose I refer to the bay or panel S, fig. 1.

This panel is composed of a series of perforated plates, *b b b b*, similar to the plate represented by fig. 3, which are placed one above another, as represented, each plate being provided with two lugs, *c c*, fig. 3, on each end, which, together with corresponding lugs on the adjacent plates in the next panel or bay, are clasped by the binder or buck-staff *d d*, said binder *d d* being divided vertically into two parts, as represented in figs. 1 and 2, these parts being secured together by two horizontal bolts, *e e*.

The top of the binder *d d* is secured to the top of the corresponding binder *f f*, on the back of the furnace, by two bolts, *g g*, one for each half of the binder.

The bottom of the binder is secured by being inserted behind a lug, *h h*, which is cast upon the front

of sill *i* of the furnace, said sill being tied to a corresponding sill on the back of the furnace by a large bolt, *k k k*, below the end of each binder.

The construction and peculiar connection of plates, binders, and sills, which is part of my invention, admit of the removal of an entire bay or panel of plates, without disturbing the adjoining panels, in the following manner: By removing that half of the binder *d d* which is in front of the plates in the bay or panel above named, all the plates can be removed at once with great ease.

The plates themselves are constructed in such a manner as to admit of a circulation of air between the plates and the brick-work of the furnace. This is accomplished in the following manner: Each plate has, on the side next the brick-work of the furnace, several vertical ribs of metal, *l l*, said ribs *l l* being either cast on the plate, or formed of bars of metal, *m m*, inserted between the plates and the brick-work. These ribs serve the purpose of keeping the body of the plate away from the brick-work, and the air entering through the perforation in the plate, has a free circulation, in a vertical direction, between the plates and the brick-work, thus keeping the plates cooler than they would be if their whole surface were in contact with the brick-work of the furnace, and enabling the workman to perform his duties with greater comfort than possible with plates of the ordinary description.

The fact that the plates are perforated, and not entirely in contact with the brick-work, enables the furnace to be heated with less fuel than is necessary in the case of plates of the ordinary description, as the fire-brick of the furnace does not radiate heat to the air as readily as the cast-iron plates would do if they were in close contact with the brick-work.

The above-described method of constructing the plates admits of their being made much thinner than those constructed in the ordinary manner, but three-quarters of an inch in thickness being required between the ribs *l l* or *m m*.

What I claim as my invention, and desire to secure by Letters Patent, is—

1. The construction of the casings of reverberatory or other furnaces, of perforated plates *b b b b*, binders *d d*, and sills *i*, all constructed, combined, and arranged substantially in the manner and for the purpose hereinbefore specified.

2. The construction of each bay or panel of the casings of reverberatory or other furnaces, of perforated plates *b b*, which are placed one above another, as hereinbefore described.

3. The construction of the casings of reverberatory furnaces, of perforated plates, with ribs *l l*, cast on the back of each, or loose bars, *m m*, inserted between the plates and the brick-work of the furnace, for the purpose hereinbefore described.

W. F. DURFEE.
